UNITED STATES PATENT OFFICE

2,112,460

OIL BURNER UNIT

Charles L. Gohmann, New Albany, Ind.

Application July 22, 1935, Serial No. 32,508

1 Claim. (Cl. 126—44)

This invention relates to an oil burner unit which is primarily intended for use in the so-called "family" oil burning cooking and heating stoves, but which is generally useful for heating purposes. In devices of this character, oil is fed from a reservoir through valved pipes to an oil burner usually containing concentric oil grooves in which circular band wicks are placed.

While these parts are variously arranged in different stoves, it is believed that reference to the general and representative arrangements usually employed will serve to make the present invention more clear. In such arrangements, the stove ordinarily contains a burner chamber extending from the front of the stove to its rear. Twin burners are suitably mounted in parallel or series between the front and rear walls of the burner chamber. An oil pipe extends from the under side of each burner forwardly to its valve adjacent the front wall. An oil supply pipe extends from the valves either rearwardly under one or both of the burners to a reservoir built in the rear of the stove, or, around the oven chamber of the stove to a reservoir on the other side thereof. With any of these arrangements, access to the various parts is limited by the stove structure while the oil feed lines are often subjected to a degree of heat sufficient to produce gasification of oil therein. Both of these results are objectionable.

The principal object of this invention is to avoid these objections and, more particularly, to provide a simple, compact structure which does not require attachment to the stove but which, on the contrary, may be inserted into and removed from the stove as a unit.

Another object is to provide a novel arrangement by which the gasification of oil in the feed lines is either eliminated or reduced to a minimum.

A further object is to provide a simple, compact unitary structure which is inexpensive to construct, install and service.

A unit constructed in accordance with my invention is illustrated in the accompanying drawings, wherein:

Figure 1 is a side elevation;

Figure 2 is a bottom plan view;

Figure 3 is a section along line 3—3 of Figure 1;

Figure 4 is a detail of the burner plate support;

Figure 5 is a partly broken section along line 5—5 of Figure 1;

Figure 6 is a section along line 6—6 of Figure 5;

Figure 7 is a section along line 7—7 of Figure 5;

Figure 8 is an enlarged section along line 8—8 of Fig. 6.

In accordance with my invention, all of the burner unit parts, i. e., the reservoir, burner, valves and oil feed pipes, are mounted upon a base so that they may be inserted into and removed from the heating chamber of the stove as a unit. The base may be constructed in any suitable form and of any suitable material. As shown, it is of rectangular skeleton form, having angle iron side members 1 which are connected together by spaced cross members 2 of T shape. At one end of the base, supporting legs 3 are provided for an oil sump 4. The sump is adapted to support at a suitable elevation an inverted reservoir, 5.

The reservoir, which is of a well known type, has a valved outlet 6 which is held closed by a suitable spring (see Figure 7) until the reservoir is inverted and positioned upon the sump, whereupon the valve stem strikes the bottom of the sump, thus opening the valve. When the valve is opened, oil flows into the sump, filling it and its outlet pipe 7, up to the flow regulating valves, until the oil level reached in the sump is higher than the lowermost portion of the reservoir valved outlet 6. At this level, air is prevented from entering the reservoir; hence, the oil flow therefrom ceases.

The burners indicated generally at 8 are also of a well-known type having a bottom plate 9 which is provided with inner and outer wick-receiving concentric oil grooves 10. These grooves are separated at all points by a flat raised ridge 11, except at the point where the oil supply pipe 12 communicates with the burner (see Fig. 8). The ridge 11 is provided with a series of short, up-right air intake pipes 13 and 40 directly over the ridge is placed another ridge member 14, having openings into which the upper ends of the air pipes 13 fit. On opposite sides of each groove 10 and of the wick contained in such groove an up-right perforated cylinder 15 45 is positioned. These cylinders, four in number, define alternate gas and air chambers. The top of each burner is also provided with a perforated cover plate 16 which fits over the cylinders 15. Naturally, when a wick is ignited, the oil begins 50 to vaporize. As the vapor rises between the perforated shells or cylinders 15, air is drawn in through the perforations and mixed with the vapor to form the combustible mixture. The draft between the shells lifts the flame entirely 55

above the wicks; hence, the latter function only to facilitate the starting of the burner. By the time the burner is hot enough to vaporize the oil in the troughs completely, the vaporizing chamber will be heated sufficiently to vaporize the oil as it enters.

The burners 8 should be supported at a level such that oil from the reservoir will cease flowing to the burners when the oil grooves in the burners are half full of oil. The burners should, of course, be properly leveled to produce a uniform depth of oil in the grooves, and such level may be obtained by adjusting the level of the stove accordingly. The burners may be directly supported on 15 or secured to the base 1. They preferably, however, are mounted on a plate 17 which is adjustably secured to the base 1 through the agency of screws 18 threaded to the base and having means at their upper ends for holding the plate. 20 When so mounted, final adjustments of the burner levels can be effected by the screws.

The sump outlet oil pipe 7 and burner supply oil pipe 12 are, of course, connected to each other through regulating valves and suitable piping. In 25 accordance with previous practice, these valves would be provided with short valve stems and located on the stove adjacent the front wall thereof or on a stand which is set apart from the stove. In accordance with my invention, 30 they are provided with long valve stems and positioned under the reservoir at the opposite or reservoir end of the unit. Accordingly, the sump outlet pipe 7 is connected directly to one side of the flow regulating valves 19 and 19-a. The 35 other side of each of the valves 19 and 19-a is connected through pipes 20 and 20-a respectively to the front and rear burners 8. The valve stems 21 and 21-a of the valves are made of a length sufficient to extend from the valves to the front 40 end of the burner unit. When the unit is positioned in the heating chamber of a stove, these valves stems will, of course, project through suit-

able openings in the front wall of the stove so that the valves may be regulated from the exterior thereof.

With the arrangement thus described, it will be appreciated that the amount of oil piping exposed to the heat of the burner is reduced to a minimum. Hence, the possibility of oil being vaporized in such pipes is likewise reduced. Such vaporization is highly undesirable because it produces an uneven and "spurting" flame. In some 10 instances, the pressure of the vaporized oil causes it to spurt sufficiently to extinguish the flame. The reduction of exposed oil piping is, of course, accomplished by placing the valves adjacent the reservoir while convenient access for regulating 15 the valves is maintained by providing them with long valve stems. It will also be appreciated that the structure herein described is very sturdy and compact and one which can be readily inserted within a heating chamber of sufficient size 20 to receive it. When any parts require adjustment or repair, such parts are, by virtue of the unitary and removable structure herein proposed, readily accessible.

Having described my invention, I claim:—

A portable oil burner unit of the type intended for insertion into and removal from the heating chamber of a stove as an unit, comprising a horizontal shallow unitary frame, an oil sump extending above and fixedly mounted on said frame 30 adjacent its rear end, said sump being adapted to receive an oil reservoir, an oil burner extending above and mounted on said frame between said sump and the front end of the frame, an oil regulating valve supported by said frame below and 35 adjacent said sump, a short oil conduit connecting said sump to one side of said valve, another oil conduit connecting the opposite side of said valve to said burner, and a long valve stem extending from said valve to the front end of said frame. 40

CHARLES L. GOHMANN.
